CLAIM

The ornamental design for a rhinoceros LCD handwriting pad, as shown and described.

DESCRIPTION

FIG. 1 is a front perspective view of a rhinoceros LCD handwriting pad showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 2;

FIG. 14 is a partial enlarged view of FIG. 2;

FIG. 15 is a partial enlarged view of FIG. 2;

FIG. 16 is a partial enlarged view of FIG. 2;

FIG. 17 is a partial enlarged view of FIG. 2;

FIG. 18 is a partial enlarged view of FIG. 2;

FIG. 19 is a partial enlarged view of FIG. 5;

FIG. 20 is a partial enlarged view of FIG. 5;

FIG. 21 is a partial enlarged view of FIG. 6;

FIG. 22 is a partial enlarged view of FIG. 6;

FIG. 23 is a partial enlarged view of FIG. 7;

FIG. 24 is a partial enlarged view of FIG. 7;

FIG. 25 is a partial enlarged view of FIG. 8;

FIG. 26 is a partial enlarged view of FIG. 8;

FIG. 27 is a partial enlarged view of FIG. 8; and,

FIG. 28 is a partial enlarged view of FIG. 8.

The broken lines in the figures are for the purpose of illustrating portions of the rhinoceros LCD handwriting pad that form no part of the claimed design and the dash-dot-dash lines are for notating areas enlarged in different views and the boundaries of those enlarged views, which form no part of the claimed design.
